WELL PUMP

Allen H. Ilfrey, Houston, Tex., assignor, by
mesne assignments, to Standard Oil Develop-
ment Company, Elizabeth, N. J., a corporation
of Delaware

Application October 4, 1951, Serial No. 249,678

13 Claims. (Cl. 103—179)

1

The present invention is directed to pumps and especially to pumps to be used in well bores in the earth's surface. More specifically, my invention is directed to an improved apparatus including in combination, a well pump and a valve therefor.

This application is a continuation-in-part of U. S. Serial No. 227,417, filed May 21, 1951, now abandoned.

The present invention may be briefly described as involving a well pump adapted to be actuated by a sucker rod extending to the earth's surface which includes the combination of a cylindrical bore defining a working barrel in which a piston member is arranged therein in sliding relationship. The pump includes at least one valve housing defining a plurality of radial passageways communicating an exterior of the housing with the working barrel at a point above the housing. A concentric deformable sleeve is arranged or mounted on the valve housing which is adapted to close the passageways when the piston member is in a first position and to open the passageways when the piston is in a second position. Means are provided to attach the piston member to the sucker rod to cause said piston member to assume said first and second position on actuation of the sucker rod. It is specifically contemplated in the apparatus of the present invention that the piston member and the valve housing may be formed integrally to define a piston member including a travelling valve arranged therein as has been described. It is also contemplated that the valve housing may define a standing valve arranged in the working barrel at a point below the piston member. It is specifically contemplated that the concentric deformable sleeve may be arranged exteriorly or interiorly on the valve housing with the exterior arrangement preferred to the interior arrangement of the concentric sleeve.

The invention will be further illustrated by reference to the drawing in which

Fig. 1 shows an arrangement of a well pump having a travelling valve and a standing valve in accordance with the present invention;

Fig. 2 is a sectional view of the travelling valve of Fig. 1;

Fig. 3 shows an arrangement of the present invention with a well pump including a piston member and a travelling valve integrally arranged therewith having a standing valve in accordance with the present invention;

Fig. 4 is a sectional view of the standing valve of Fig. 3;

Fig. 5 shows an arrangement of a piston includ-

2

ing a travelling valve in accordance with the present invention with a standing valve arranged therebelow;

Fig. 6 shows an arrangement of well pump having a travelling valve and a standing valve in which the deformable sleeve is arranged exteriorly on the travelling valve and standing valve;

Fig. 7 is a sectional view of the travelling valve of Fig. 6;

Fig. 8 is a sectional view of the standing valve of Fig. 6;

Fig. 9 shows an arrangement of the present invention with a well pump including a piston member and travelling valve integrally arranged therewith having a standing valve including a deformable sleeve arranged exteriorly on the standing valve; and

Fig. 10 shows an arrangement of a piston including a travelling valve having a deformable sleeve exteriorly thereon with a standing valve arranged below the traveling valve and piston.

In the several figures of the drawing, identical parts will be identified by identical numerals.

Referring now to the drawing and particularly to Fig. 1, numeral 11 designates a cylindrical bore which is attached to the producing string in a well extending into a producing formation in the earth's surface. The cylindrical bore 11 defines a working barrel 11 which is preferably formed of pipe having a smooth interior section and which may be constructed of a corrosion resistant metal, such as stainless steel. Arranged in the working barrel 11 is a piston member 12 including a travelling valve 13 having a plurality of radial passageways 14. The piston member 12 and the travelling valve 13 will be described in more detail hereinafter. Attached to the working barrel at a point below the piston member 12 and the travelling valve 13 is a housing cage 15 in which is arranged a standing valve 16 which defines a plurality of radial passageways 17. The travelling valve 13 and the standing valve 16 each have a concentric internal sleeve 18 and 19, respectively, constructed of a deformable material, such as synthetic rubber, which is resistant to oil. Connected to the lower end of the housing cage 15 is a conventional gas anchor 20. The travelling valve 13 is provided with a cap 21 and the standing valve 16 is likewise provided with a cap 22. It will be seen that the piston member 12 and the travelling valve 13 form an integral member which is attached to a sucker rod 23 which extends through the well bore to the earth's surface to a suitable actuating means therefor.

Referring now to Fig. 2 which is a cross-sec-

tional view of the travelling valve of Fig. 1, it will be seen that the piston member 12 and the travelling valve 13 are formed integrally as a single unit, the piston member 12 being provided with packing or pump cups 24 which makes a sliding fit with the working barrel 11 and seals same on movement of the piston member 12 and the travelling valve 13 upwardly and downwardly in the working barrel 11. The piston member 12 and the travelling valve 13 include a perforated sleeve 25 defining passageways 14 arranged in which is an internal concentric deformable sleeve 18. The sucker rod 23 is attached to cap 21 and serves to move the piston member 12 and the travelling valve 13 upwardly and downwardly in the working barrel 11. The internal sleeve 18 is provided with a shoulder 26 which forms a seal with the sleeve 25 and the cap 21. Thus the inner sleeve 18 and the perforated sleeve 25 having radial passageways 14 therein communicate with the working barrel at a point above the assembly including the piston 12 and the travelling valve 13 by means of a passageway defined by the perforated sleeve 25 and the internal concentric sleeve 18 when there is a pressure differential between the outer and inner surface of sleeve 18, allowing communication from the passageways 14 to the working barrel 11 at a point above the assembly.

Referring now to Fig. 3, it will be seen that 30 piston assembly 12 and the travelling valve 13 of Fig. 1 have been replaced by a piston member 30 provided with a packing means 31 in which a conventional ball and seat travelling valve 32 is arranged integrally therewith. The travelling 35 valve 32 includes a cage 33 in which is a ball check valve 34 which fits on a seat, not shown, the whole assembly being attached to a sucker rod 23, as shown in Fig. 1. The piston 30 and the travelling valve 32 are arranged in a working 40 barrel 11 to which is attached a cage 15 in which is arranged a standing valve 16 connected to the working barrel 11, as shown. The standing 45 valve 16 is similar to the standing valve of Fig. 1 and similar thereto defines a plurality of radial passageways 17. The cage 15 is attached at a lower end to a gas anchor 20. The standing valve 16 is provided with a cap 22 to close the lower end thereof.

Referring to Fig. 4, it will be seen that the 50 standing valve 16 is attached to the cage 15 which, in turn, is attached to the working barrel 11. It will be further clear that the standing valve 16, in accordance with the present invention, includes a sleeve 40 defining the radial passageways 17. Arranged in sleeve 40 is a concentric sleeve 19 constructed of a deformable material. The sleeve 19 and the sleeve 40 define a passageway 41 when there is a pressure differential between the outer and inner surfaces of sleeves 19, which allows communication between passageways 17 and the interior of the working barrel 11. As described with respect to Fig. 1 and Fig. 3 the lower end of the standing valve 16 is provided with a cap 22 connected to the sleeve 40, the internal sleeve 19 being provided with a shoulder 42 which makes a snug fit with the cap 22 and the sleeve 40.

Referring now to Fig. 5 a travelling valve in accordance with Figs. 1 and 2 is arranged in a working barrel 11. Arranged below the travelling valve 13 in Fig. 5 is a standing valve 50 provided with a cage 51 arranged in which is a conventional ball and seat valve in which the ball 52 is shown. The standing valve 50 is connected

by a coupling 53 to the working barrel 11 and to a gas anchor 20 which is of conventional construction. In this embodiment of the invention a travelling valve in accordance with the present invention is spaced above a standing valve.

Referring to Fig. 6, numeral 11 designates a cylindrical bore which is attached to the producing string in a well extending into a producing formation, the cylindrical bore 11 defining a working barrel. Arranged in the working barrel 11 is a piston member 60 including a travelling valve 61 which will be described in detail hereinafter. Attached to the working barrel 11 at a point below the piston member 60 and the travelling valve 61 is a housing cage 62 in which is arranged a standing valve 63 which will be described in more detail hereinafter. Connected to the lower end of the housing cage 62 by mating threads 64 is a conventional gas anchor 20. The standing valve 63 is threaded connected by mating threads 65 to the cage 62. It will be noted that the piston 60 and the travelling valve 61 are attached to a sucker rod 23 which extends through the well bore to the earth's surface to a suitable actuating means therefor, not shown.

In Fig. 7 is a cross-sectional view of the travelling valve and the piston of Fig. 6. It will be noted that the piston 60 and the travelling valve 61 are formed integrally as a single movable unit, the piston member 60 being provided with packing members 66 which make a sliding fit with the working barrel 11 and seals same on movement of the piston member 60 upwardly and downwardly in the working barrel 11. The piston member 60 and the travelling valve 61 include a perforated sleeve 67 defining passageways 68. Arranged concentrically and exteriorly on the perforated sleeve 67 which form a valve housing is a deformable sleeve 69 which on its lower end is provided with a shoulder 69a. The deformable sleeve 69 is clamped to the perforated sleeve 67 by means of an annular clamp 70a which is arranged immediately above the shoulder 69a and causes a sealing of the sleeve 69 to the perforated sleeve 67. The sucker rod 23 is attached to a cap 70 which serves to close the upper end of the travelling valve 61 and the piston 60. The piston member 60 of the travelling valve 61 has an internal bore 71 which allows communication from below the piston 60 and the travelling valve 61 to the working barrel above the piston 60 and travelling valve 61 through passageways 68, as will be described further hereinafter.

In Fig. 8 a standing valve in accordance with the present invention is described which is threaded connected by threads 65 to the cage 62 which, in turn, is connected by mating threads 72 to the working barrel 11. The standing valve 63 comprises a valve housing or internal sleeve 73 which defines a plurality of radial passageways 74 which communicate with an internal bore 75 of the standing valve 63 which connects to the gas anchor 20. Arranged exteriorly on the sleeve 73 is a concentric deformable sleeve 76 which is provided with a shoulder 77 at its lower end and which is clamped against the perforated sleeve 73 by an annular clamp 78 which makes a tight fit between the sleeve 73 and the sleeve 76. It will be noted that the upper end of the standing valve 63 is closed by a plate 79 while the lower end is open to let the internal bore 75 communicate with the gas anchor. Communication between the bore 75 of the working barrel 11 above the standing valve 63 is through the passageways 74 as will be described further.

Referring now to Fig. 9, it will be noted that the piston assembly 60 and the travelling valve 61 of Figs. 6 and 7 have been replaced by a piston member 60 provided with sealing means 61 and a conventional ball and seat travelling valve 62 arranged integrally therewith. The travelling valve 62 includes a cage 63 in which is a ball check valve 64 which lifts on a seat, not shown, the whole assembly being attached, as shown in Fig. 9, to sucker rod 23. The piston 60 and the travelling valve 62 are arranged in the working barrel 11 to which is attached a cage 62 in which is arranged a standing valve 63 in accordance with the present invention, the cage 62 being connected to the working barrel 11 by mating threads 72. The standing valve 63 is similar to the standing valve of Figs. 6 and 8 and similar thereto has arranged exteriorly thereon a concentric deformable sleeve 69 and defines with the internal sleeve 13 radial passageways 74, the cage 62 being attached by mating threads 64 to the gas anchor 20 and the standing valve 63 being attached to the cage by mating threads 65.

In Fig. 10 the travelling valve 61 and piston 60 are arranged integrally therewith and are constructed in accordance with the present invention while standing valve 100 is of conventional design and is similar to the standing valve 62 in Fig. 7. The standing valve 100 comprises a cage 101 in which is arranged a ball check valve 102 which is designed to fit on a seat not shown. The standing valve 100 is threaded connected to cage 103 by mating threads 104, the cage 103 being connected to the working barrel 11 by mating threads 105 and to the gas anchor 20 by mating threads 106.

In operation the apparatus of the present invention with reference particularly to Figs. 1 and 2 in which both a travelling valve and a standing valve in accordance with the present invention is shown it is assumed that the sucker rod 23 is connected to a suitable motivating means which causes the piston member 12 to reciprocate upwardly and downwardly in the working barrel 11. As the piston member 12 including the travelling valve 13 moves down to a first position, the internal sleeve 13, with reference to Fig. 2, is caused to move inwardly and open the radial passageways 14. With reference to Fig. 4, the hydrostatic head causes the internal sleeve 13 to bulge and close passageways 17. On upward movement of the sucker rod 23, referring again to Figs. 1, 2 and 4, the fluid from the producing formation from which fluid is being produced flows into the passageway defined by the inner surface of sleeve 48 and the inner sleeve 19 through passageways 17 and causes collapsing of the sleeve 13 allowing the fluid to pass upwardly therethrough into the working barrel 11. When fluid is flowing into the working barrel 11 by collapsing of the sleeve 13 on upward movement of the sucker rod 23, the sleeve 13 is caused to bulge outwardly and close the radial passageways 14. Similarly, with reference to Figs. 1 and 2 on downward movement the fluid passes from the working barrel 11 through the passageways 14 into annular space between sleeve 25 and sleeve 18 on collapsing of the sleeve 13 and thence into the barrel 11 above the piston member 12 and travelling valve 32.

The device of Figs. 3 and 5 works in a similar manner to that described with the exception in Fig. 3 the travelling valve 13 of Fig. 1 has been replaced by a travelling valve and piston embodying a ball and seat arrangement. The

standing valve 16 is that of Fig. 4 and works in the manner described.

In the arrangement of Fig. 5 the fluid passes through the standing valve 50 on upward movement of the piston 12 and the travelling valve 13 causes flow therethrough and then flows through the travelling valve 13 and upward into a working barrel 11 on downward movement of the piston 12 as has been described.

The device of Figs. 6 to 10 operates in a similar manner to the device of Figs. 1 to 5. Referring particularly to Figs. 6, 7, and 8 on downward movement of the sucker rod 23 the piston 60 and travelling valve 61 causes compression of the liquid in the working barrel 11 below it and this liquid seeks to move upwardly through the internal bore 71. As a result of the downward movement of the piston 60 and travelling valve 61, the compressed liquid is forced out through radial passageways 68 and causes the deformable sleeve 69 to be bulged outwardly allowing the fluid from the internal bore 71 to pass through the passageways 68 and into the working barrel 11 above the travelling valve 61. On upward movement of the piston 60 in travelling valve 67 a pressure differential is created in the working barrel 11 between the piston 60 and the internal bore 75 of the standing valve 63, the pressure in the internal bore 75 being greater than that in the working barrel 11 below the piston 60. As a result the fluid from the producing formation flows into the internal bore 75 through the radial passageways 74 and causes the sleeve 73 to be bulged outwardly allowing passage of fluid from the bore 75 to the working barrel 11 above the standing valve 63.

The device in accordance with Figs. 9 and 10 operates in a similar manner. Referring to Fig. 9, on downward movement of the piston 98 the ball and seat check valve 94 is unseated and allows fluid to pass from the internal bore, not shown, which communicates by an open lower end with the working barrel 11, of the piston member 99 upwardly therein and to working barrel 11 at a point above the travelling valve 92. On upward movement of the piston 98 and the travelling valve 92 the standing valve 63 is caused to operate in a manner which has been described.

In Fig. 10 the operation of the piston 60 and travelling valve 61 is, as has been described with respect to the other figures, the standing valve 100 is caused to open by upward movement of the piston 60 in travelling valve 61 by actuation of sucker rod 23 which causes the ball 100 to unseat and allow fluid to flow through the internal bore, not shown, of valve 100 and cage 101 into the working valve 11 above it.

It will be noted from the several embodiments of my invention that I may use a travelling valve including a perforated sleeve defining radial passageways having an internal or external concentric sleeve of deformable material and I may have a standing valve constructed in a similar manner. Alternatively, I may employ a standing valve constructed in accordance with the present invention and employ a ball and seat or other type of travelling valve as has been illustrated or I may use a travelling valve and piston in accordance with the present invention and have a ball and seat or other type of standing valve. Regardless of the particular combination that I use, it is to be emphasized that, in the apparatus of my invention, it is contemplated that at least one valve member in a well pump may be defined by a perforated sleeve defining radial pas-

sageways with a concentric sleeve constructed of a deformable material, the assembly being closed at one end and open at the other end, communication from the lower to the upper end being had through the radial passageways and then upwardly into a working barrel, as has been described.

It is exceedingly desirable to replace at least either the traveling or the standing valve with a valve in accordance with the present invention 10 including a deformable sleeve since the combination of an outer sleeve and an inner sleeve with one of the sleeves defining radial passageways eliminates difficulties due to improper seating of a ball and seat valve or similar mechanism; such latter mechanism may not seat properly because of abrasive particles deposited on the seat and causing imperfect sealing on the down-stroke. With my invention it will be clear that the arrangement of the internal sleeve and the 20 external sleeve is in vertical relationship and, consequently, it is impossible for material to deposit thereon and interfere with the sealing.

The nature and objects of the present invention having been completely described and illustrated, what I wish to claim as new and useful and to secure by Letters Patent is:

1. In a well pump adapted to be actuated by a sucker rod extending to the earth's surface, the combination of a cylindrical bore defining a working barrel, a piston member arranged in the working barrel in sliding relationship thereto and at least one valve housing defining a plurality of radial passageways communicating an exterior of the housing with said working barrel at a point above the housing, a concentric deformable sleeve mounted on and secured to said housing at one end and having a free end, said sleeve flexing to close said passageways when the piston member is in a first position and to open said passageways when the piston member is in a second position, and means attaching said piston member to said sucker rod to cause said piston member to assume said first and second positions on actuation of said sucker rod.

2. Apparatus in accordance with claim 1 in which the piston member and the valve housing define a travelling valve arranged integrally therewith.

3. Apparatus in accordance with claim 1 in 50 which the valve housing defines a standing valve arranged in said working barrel at a point below said piston member.

4. Apparatus in accordance with claim 1 in which the deformable sleeve is mounted interiorly on said valve housing.

5. Apparatus in accordance with claim 1 in which the deformable sleeve is mounted exteriorly on said valve housing.

6. Apparatus in accordance with claim 1 in which the valve housing has a closed upper end and an open lower end and the deformable sleeve is mounted exteriorly on said valve housing.

7. Apparatus in accordance with claim 1 in which the valve housing has a closed lower end and an open upper end and the deformable sleeve is mounted interiorly on said valve housing.

8. Apparatus in accordance with claim 1 in which the piston member has a travelling valve arranged integrally therewith and the valve housing is arranged in said working barrel below said piston member.

9. Apparatus in accordance with claim 1 in which the piston member and the valve housing define a travelling valve arranged integrally therewith and in which a standing valve is arranged in the working barrel below the piston member.

10. Apparatus in accordance with claim 6 in which the piston member and the valve housing define a travelling valve arranged integrally therewith.

11. Apparatus in accordance with claim 6 in which the valve housing defines a standing valve arranged in said working barrel at a point below said piston member.

12. Apparatus in accordance with claim 7 in which the piston member and the valve housing define a travelling valve arranged integrally therewith.

13. Apparatus in accordance with claim 7 in which the valve housing defines a standing valve arranged in said working barrel at a point below said piston member.

ALLEN H. ILFREY.
